POWER FLOATS

Robert L. Stevens, Boston, N. Y., assignor to Wiesner-Rapp Company, Inc., Buffalo, N. Y.

Application October 13, 1953, Serial No. 385,731

7 Claims. (Cl. 94—45)

My invention relates in general to a machine for treating the surfaces of cementitious bodies and specifically to a troweling compactor for floating and finishing cement floors and the like.

As is well known to those skilled in the art, in the surface treatment of cementitious bodies, it is the practice to begin the troweling action upon the surface at a relatively slow speed with the trowel at a small angle or pitch, but as the cement mixture gets harder, the speed of movement of the trowel and the angle or pitch is increased.

The principal object of my invention is to provide a device in which the speed of rotation and the angular relation of the blade in respect to the surface being treated may be increased during the treatment of the surface.

Another object is to provide hydraulic means for changing the angle of attack of the blade.

A further object is to provide hydraulic blade-lifting means automatically controlled by the speed of the driving motor or power means.

A further object is to provide a rotary troweling device having a plurality of blades adjustable in unison.

Moreover, my device is of such a nature that the hydraulically-actuated means of each trowel under normal working conditions is distended an amount equal to the hydraulically-actuated means of the other trowels, each of the members being sufficiently resilient to permit additional momentary expansion to allow the associated blade to move independently when striking a stone or other foreign object without changing the angle of the other blade.

Furthermore, each of the blades of my device is individually actuated by means of an inflatable member receiving fluid under pressure produced by inexpensive means connected to the motive power and controlled by the speed thereof.

The above objects and advantages have been accomplished by the device shown in the accompanying drawings, of which:

Fig. 1 is a side elevation, partly in section of my complete device;

Fig. 2 is a reduced side elevation of the same;

Fig. 3 is a plan view of the device;

Fig. 4 is an enlarged fragmentary isometrical perspective view of one of the trowels and associated means;

Fig. 5 is an enlarged sectional view of the trowel and is taken on line V—V of Fig. 4; and,

Fig. 6 is an enlarged fragmentary view of the flexible means.

The device comprises a casing 10 having a top wall 11 and a bottom wall 12 provided with a removable cover plate 13. A main shaft 14 is mounted for rotation in suitable bearings carried by the upper wall of the casing and the cover plate. Also carried by the upper wall 11 is a gear support 15 in the form of a vertically arranged tube 16 secured to the casing wall and having a gear shaft 17 rotatably mounted therein. The lower end of the gear shaft 17 projects into the casing and is provided with a driving sprocket 18 which is connected to a driven

2

sprocket 20, carried by the main shaft 14, by means of a sprocket chain 21.

The upper end of the gear support is formed with a gear casing 22 in which is mounted a driven bevel gear 23 carried by the upper end of the gear shaft 17. A driving gear pinion 24 meshes with the gear 23 and is mounted upon a pinion shaft 25 rotatably supported by the gear housing 22 and extending out beyond the housing where it is provided with a driven sheave 26.

10 Any suitable form of motive power may be provided for the device, but I prefer to use an internal combustion engine 30 of any conventional type. The driven sheave 26 is connected to the usual drive pulley 31 of the engine by means of a belt 32. In order to connect and disconnect the motive power with the driven sheave 26, I employ a bell crank lever 38 which is pivotally carried by the engine upon a pivot pin 33. The lever 38 has a control arm 34 which is connected by means of a rod 35 to a control lever 36 mounted upon the upper end of the handle 40 of the device. The bell crank lever is also formed with an idler arm 41 which carries an idler wheel 42 at its outer end. The idler wheel is designed to bear against the outer surface of the belt 32, so as to take up the slackness in the belt when it is desired to connect the motive power with the device. The lower end of the handle 40 is suitably attached to the housing, whereby the device may be moved about over the surface being treated.

Carried by the lower projecting end 43 of the main shaft 14 is a driving head 44 which carries a number of arms 45, preferably five in number. Each of these arms carries a trowel holder 46 secured to its under surface. Each trowel holder is formed with an integral bearing block 50 near its extreme ends for supporting a pivot rod 51. A trowel 52 is disposed beneath each of the trowel holders, and each carries a bearing 53 at each end, one of which is pivotally mounted upon each of the projecting ends of the pivot rod 51. As clearly shown in Figs. 4 and 5, each of the trowels is provided with a stiffening member 54 preferably of angle iron cross section which extends preferably the length of the trowel. It is desirable that the trowels be normally held in the position shown in Figs. 4 and 5 and to accomplish this I employ a hold-up spring 55 which may be mounted about the pivot rod, having one end fixed to the block or bearing against the holder, and the other end bearing against the trowel on the opposite side of its pivot point.

As shown in Figs. 4 and 5, the holder is spaced from the trowel 52 and is maintained in this spaced relation by means of a flange 56 formed on the edge thereof opposite the pivot rod. Within this space is mounted the inflatable member 60 of my device. Each of these inflatable members is preferably formed from circular tubing of resilient material or the like, having the opposite sides fastened together at the ends 61 in fluid-tight manner by means of an end clip 62. As shown in Fig. 5 each inflatable member is formed with a metallic stem 63 which is suitably secured in the wall of the member and which extends up through openings 64 formed in the holder and in the arm. The stem is formed with a central passageway through which fluid under pressure may be supplied to the flexible member.

Since the angle relation of the trowels is governed by fluid pressure, a suitable fluid pump 65 is provided. This pump is preferably arranged on top of the gear casing 22, and is driven by means of a shaft 66 which is connected to the gear shaft 17 in any suitable manner. The outlet 67 of the pump is connected to a supply pipe 70. This supply pipe is connected to a supply head 71 disposed within the casing 10 and rotatably connected to the main shaft 14. The supply head is formed with a central aperture 72

which communicates with a central aperture 73 formed in the main shaft. A fluid distributing head 74 is mounted about the lower end of the main shaft below the cover plate 13 and it is formed with an annular groove 75 which is in communication with the central passageway 73 of the shaft through a lateral passageway formed therein. The distributing head is provided with a number of fluid outlets equal in number to the number of trowels, and a distributing pipe 76 connects each of the outlets with one of the stems 63 of the inflatable members. A fluid reservoir 80 is mounted preferably upon the casing 10, and a suction pipe 81 connects this reservoir with the fluid pump 65. A pressure regulating valve 82 of any suitable type is mounted in the supply line 70 extending to the supply head and it is provided with a return pipe 83 connecting the relief outlet valve with the reservoir. This pressure regulating device is adjusted to supply fluid at the desired pressure to the flexible members of the device. The usual throttle control 86 is carried by the handle, whereby the speed of rotation of the main shaft may be regulated, thereby regulating the amount of distension of the inflatable members and the angular relation of the trowels. A guard ring 84 is provided for the device, which has an outer diameter slightly larger than the outer sweep of the trowels. This ring is carried by radiating arms 85 which are secured to the casing 10.

When the device is to be used, the control handle 36 is actuated to connect the motive power with the main shaft 14 through the belt and gears above described. As is well known the first action of a trowel upon freshly mixed cement or concrete is that of dragging or floating with the trowels in substantially flat position. However, as the cement starts to harden, the angle of the trowels with the cementitious surface is increased; and the troweling is completed by the trailing edges of the trowels. In order to change the angle of the trowels, the motor is speeded up, the pressure of the fluid is increased, and the trowels are automatically tilted by the distending action of the inflatable members. The position of the trowels with respect to the surface being treated is therefore under the control of the operator at all times and the trowels may be accurately adjusted in unison to treat the cement at the various stages during the hardening period without stopping the device to make the adjustment. The inflatable members while being distended to maintain all of the trowels simultaneously at the same angle, should one of the trowels come in contact with a stone or other foreign substance, the inflatable member of this trowel will momentarily yield individually to the impact without disturbing the angle of the other trowels.

What is claimed is:

1. In a power float, a revolving head having radiating arms and formed with a central passageway, a trowel assembly carried by each arm, comprising a trowel holder rigidly attached to the arm, a trowel disposed on the under side of the holder and having pivotal connection therewith, an inflatable member disposed between and in contact with each holder and the cooperating trowel, conduit means connecting each of the members with the passageway, and means connected to the central passageway and controlled by the speed of rotation of the head for supplying fluid under variable pressure to the members to alter the angular position of the trowels.

2. In a power float, a revolving head having radiating arms and formed with a central passageway, a trowel assembly carried by each arm, comprising a trowel holder rigidly attached to each arm and formed with spaced bearing blocks arranged along one side thereof, a spacing flange formed along the opposite side of the holder, a pivot rod carried by the blocks, a trowel disposed on the under side of the holder and having bearings pivotally mounted upon the pivot rod, an inflatable member for each assem-

bly mounted between and in contact with the holder and the trowel, conduit means connecting each of the members with the passageway, and variable fluid pressure means connected to the passageway of the head, whereby to alter the angular position of the trowels.

3. In a power float, a revolving head having a central passageway, a plurality of trowel assemblies carried by the head and radiating therefrom, each assembly comprising a trowel holder rigidly attached to the head, a trowel pivotally mounted upon and underneath the holder, an inflatable member disposed between and in contact with each cooperating holder and trowel, conduit means connecting the head passageway with each of the members, and fluid pressure supply means connected to the passageway of said head.

10 4. In a power float, a revolving head having a central passageway, a plurality of trowel assemblies carried by the head and radiating therefrom, each assembly comprising a trowel holder rigidly attached to the head, a trowel pivotally mounted upon and underneath the holder, an inflatable member disposed between and in contact with each cooperating holder and trowel, conduit means connecting each of the members with the passageway, and means connected to the central passageway and controlled 15 by the speed of rotation of the head for supplying fluid under variable pressure to the members to alter the angular position of the trowels.

5. In a power float, the combination with a housing, and power means carried by the housing, of a rotatable 20 head carried by the housing and connected to the power means, the head being formed with a central passageway, a plurality of radiating trowel assemblies carried by the head, each assembly comprising a trowel holder fixed to the head, a trowel pivotally mounted beneath the holder, expandable means disposed between and in contact with the holder and the trowel, conduit means connecting each 25 of the expandable means to the central passageway, and fluid pressure supply means supported by the housing and connected to the central passageway of the head for controlling the angular position of the trowels.

6. In a power float, the combination with a housing, and power means carried by the housing, of a rotatable head carried by the housing and connected to the power means, a fluid passageway carried by the head, a plurality 45 of radiating trowel assemblies carried by the head, each assembly comprising a trowel holder fixed to the head, a trowel pivotally mounted beneath the holder, expandable means disposed between and in contact with the holder and the trowel, conduit means connecting each of the expandable means to the central passageway, and means connected to the fluid passageway and controlled by the speed of rotation of the head for supplying fluid under variable pressure to the expandable means to alter the angular position of the trowels.

55 7. In a power float, the combination with a housing, and power means carried by the housing, of a rotatable head carried by the housing and connected to the power means, said head being formed with a central passageway, a plurality of trowels carried by and radiating from the head for rotation therewith, a holder for each trowel carried by said head, each trowel being in the form of a blade independently pivoted beneath the holder for individual angular movement therewith, inflatable means disposed between and in contact with each holder and cooperating trowel, conduit means connecting each of the inflatable means with the passageway of the head, and variable fluid pressure supply means connected to the central passageway to alter the angular position of the trowels.
